UNITED STATES PATENT OFFICE.

ANDERS AKESON, OF BOSTON, MASSACHUSETTS, ASSIGNOR TO THE
ATLAS LIGHT & POWER COMPANY, OF BOSTON, MASSACHU-
SETTS.

CARBURETER.

SPECIFICATION forming part of Letters Patent No. 772,551, dated October 18, 1904.

Application filed April 14, 1904. Serial No. 203,202. (No model.)

To all whom it may concern:

Be it known that I, ANDERS AKESON, a citizen of the United States, residing at the city of Boston, in the county of Suffolk and State 5 of Massachusetts, have invented certain new and useful Improvements in Carbureters, of which the following is a specification.

My invention relates to the class of carbureters and is an apparatus arranged to receive 10 from a proper source compressed air and to pass the same through and over a volatile hydrocarbon, such as naphtha or gasolene, for the purpose of mingling said air with the hydrocarbon vapor in order to produce an illuminating carbureted air of great lighting power, 15 said hydrocarbon being fed to the generator by means of wicks and vaporized and filtered by means of sponge and permeable pads held in suitable receptacles.

With this object in view my invention consists of the novel construction and combination of the several parts, as hereinafter described, and specifically set forth in the claims.

In the accompanying sheet of drawings, Fig. 25 ure 1 represents a view of my improved carbureter as seen partly in elevation and partly in central vertical section. Fig. 2 is a view in elevation of the wire basket containing sponges and the means of suspending it with- 30 in the carbureter. Fig. 3 is a perspective view of the mass of sponges and wicking secured together by wires and used in generating the carbureted air from the naphtha or gasolene in the lower part of the generator.

Like numerals indicate like parts in the different views of the drawings.

In Fig. 1 is shown a carbureter connected by a pipe. The carbureter consists of a metallic receptacle of proper dimensions, preferably cylindrical in shape, and comprising the tubular portion 1, the dome 2, and the bottom 3, the same being provided with flanges and riveted together, as plainly illustrated in Fig. 1. A series of L-shaped brackets 4 are secured to the tubular portion 1, and on the inner side thereof, by means of rivets 5 or otherwise, and upon these brackets rests a circular piece 6, of wire-gauze, having a central opening or aperture. A collar 7, having a

vertical annular flange, lies upon the piece of 50 wire-gauze 6, and bolts 8 pass through the collar 7, wire-gauze 6, and brackets 4, and so hold the said wire-gauze securely in position. This piece 6, of wire-gauze, constitutes a horizontal partition and is located above the bottom 3 of the carbureter, but parallel to it. It thus divides the carbureter into two compartments, the lower one of which contains a suitable quantity of naphtha, gasolene, or other fluid hydrocarbon, as seen in Fig. 1. A T- 60 shaped coupling 9 has the three pipes 10, 11, and 12 connected thereto. The pipe 11 extends through a boss 13, which is perforated to allow its passage, and an elbow-coupling 14 fits on the inner end of the pipe 11. A 65 downwardly-extending pipe 15 has its upper end fitted in the elbow-coupling 14, and its lower end is submerged, as shown in Fig. 1.

Naphtha, gasolene, or other suitable fluid hydrocarbon is fed in proper quantities and 70 at proper intervals through the pipe 12 and flows into the lower compartment of the carbureter through the pipes 11 and 15.

Compressed air from any suitable source 75 flows through the pipes 10, 11, and 15 under pressure.

On the top of the partition 6 of wire-gauze are laid or packed a number or mass 16 of sponges, preferably of the large size known as "bath-sponges," and these are held down 80 or confined closely to the wire-gauze partition 6 by a netting 17, of copper wire, as seen in Figs. 1 and 3. A number of strands of cotton wicking 18 are passed through the mass of sponges, as best illustrated in Fig. 3, 85 and the loose ends of said wicking extend down through the metallic ring 19 (which is mounted in the central opening or aperture of the wire-gauze partition 6, as shown in Fig. 1) and dip into the liquid hydrocarbon. 90

Under the dome 2 in the upper compartment of the carbureter is suspended a wire basket or cage 20, filled with pieces 21 of dry sponge. This wire basket is shown in perspective in Fig. 2, where it is seen that it has 95 a circular slightly-dished cover 22, furnished with loops or eyes on its edge, to which the wires are fastened. A tube 23, whose exterior

surface is screw-threaded, is mounted on the cover 22 and passes through said cover. A nut 24, engaging with the tube 23 on the outside thereof, serves to draw the upper surface 5 of the cover 22 up into snug contact with the under surface of the dome 2, as shown in Fig. 1.

A pressure-gage 25 is mounted as usual on a pipe 26, which extends up from the pressure-gage chamber 27. A valve 28 is provided for the pipe 26. The chamber 27 has an annular flange 29 and is fastened by bolts 30, through the flanges 29, to the exterior of the dome 2. There is a pipe connection from 15 the carbureter to the gasometer consisting of the pipes 31, 32, 33, 34, and 35, the elbow-couplings 38 and 39, and the filtering-chamber 41. A valve 42 is between the pipes 31 and 32.

Having thus described the parts and construction of my improved gas-machine, I will now explain its mechanical principle and mode of operation.

In order to obtain a flow of carbureted air for illuminating purposes, it is necessary that 25 there should be a tank or supply of compressed air entering through the pipe 10 with sufficient pressure to force it through the several filtering-compartments and pipes and to discharge from the gasometer. (Not shown.) 30 In this passage of the compressed air through this machine it is mingled and charged to its utmost capacity with hydrocarbon vapor, and is thus changed into carbureted air capable of giving a strong and intense light. Instead, 35 however, of using compressed air for this purpose and providing means of pressing and discharging the same (which means are not shown in the drawings, but are understood to be any of the well-known means for that purpose) it is 40 obvious that common illuminating-gas from the street-main may enter under its usual pressure into the pipe 10 and in traversing the several compartments of my machine and the pipes thereof may be carbureted or highly en- 45 riched in carbon, and may therefore burn with greater intensity and increased candle-power. The carbureting compound is any suitable fluid hydrocarbon, preferably a petroleum product, such as naphtha or gasoline, which is 50 fed through the pipe 12 by any suitable means (not shown) and flows into the tank 1 to a considerable depth, as illustrated in Fig. 1. This liquid and the compressed air are discharged into the lower compartment, as shown, by the 55 submerged pipe 15, so that the compressed air bubbles up through said liquid and is saturated with it. The loose ends of the many pieces 18 of cotton wicking which, as shown, are dipped or floating in the naphtha or gasoline are com- 60 pletely saturated thereby and convey the same by capillary attraction to the mass of sponge 16, in which said strands of wicking 18 are embedded, and thus keep said mass of sponge 16 moist with said liquid hydrocarbon. Thus the 65 compressed air after being bubbled up through

the naphtha or gasoline and becoming charged therewith passes up through this moist mass of sponge 16 into the upper compartment of the carbureter and in so passing is charged to its utmost capacity with the hydrocarbon vapors. This sponge mass is peculiarly adapted to facilitate the volatilization of the hydrocarbon, as this material is exceedingly porous in its nature, readily absorbing moisture, and dividing and separating it, thus greatly increasing the area of exposure to the air. In this manner the hydrocarbon is vaporized and effectively changed into an aeriform condition and as such fills the upper compartment of the carbureter; but this vapor, though highly inflammable, requires condensation and much filtration in order to become a suitable illuminant. These results are accomplished in my machine as follows: The only outlet of the carbureter is the pipe 23; but the vapors must 70 first pass through the mass of dry sponges contained in the wire basket or cage 20. These sponges 21, being full of pores both large and small, strain out from the vapor passing 75 through them any excess of moisture and tend 80 to make the carbureted air not only drier but 85 more finely divided or finer.

I claim as a novel and useful invention and desire to secure by Letters Patent—

1. In a carbureter, the combination of a 95 closed tank divided into two compartments by a screen or perforated partition and adapted to receive and hold in its lower compartment a liquid hydrocarbon and an aeriform fluid under pressure; a layer of sponges upon the 100 screen or partition in the upper compartment; and a mass of wicking connected to and extending down loosely from said layer of sponges with the ends of said wickings submerged in said liquid hydrocarbon in the lower 105 compartment, substantially as specified.

2. In a carbureter, the combination of a receptacle; a mass of sponges supported therein and a mass of wickings connected to and extending from the mass of sponges, substantially as shown and for the purpose specified.

3. In a carbureter, the combination of a receptacle; a perforated screen or partition therein; a mass of sponges upon said screen or partition; a wire-netting adapted to confine 115 and fasten said mass of sponges upon the screen or partition; and a mass of wickings secured to the mass of sponges with their ends hanging loosely therefrom, substantially as specified.

4. In a carbureter, the combination of a carbureter; a horizontal screen or perforated partition mounted therein and having a central ring; a mass of sponge upon said screen or partition; and a mass of wicks connected to 125 said mass of sponge and having their loose ends protruding down through said ring, substantially as specified.

5. In a carbureter, the combination of a closed tank; a horizontal screen or perforated 130

partition mounted therein and having a central ring; a mass of sponge upon said screen or partition; a wire-netting securing said mass of sponge to the screen or partition; and a mass of wicks held to said mass of sponge by said wire-netting and having their loose ends protruding down through said ring, substantially as specified.

6. In a carbureter, the combination of a 10 disk having a central aperture; a tube fitting into said aperture; a basket composed of wire-netting secured to the edge of said disk; and a mass of sponges contained in said basket, substantially as specified.

15 7. In a carbureter, the combination of a closed tank having three compartments; a horizontal screen or partition mounted therein and dividing the lowest compartment from the middle compartment; a supply-pipe entering 20 the lowest compartment and adapted to discharge therein an aeriform fluid under pressure and a liquid hydrocarbon; a mass of sponge in the middle compartment resting on said screen or partition; a mass of wicks connected to the mass of sponge and having their 25 loose ends protruding through said screen or partition and extending into said lowest compartment; and an upper compartment in the top of said tank comprising a disk with a central outlet-pipe; a basket of wire-netting attached to the edge of said disk; and a mass of dry sponge contained in said basket, substantially as specified.

8. In a carbureter, the combination of a 35 closed tank having an outlet at its upper end; a mass of sponges supported in position in or near the bottom of the tank; means adapted to saturate said sponges with a liquid hydrocarbon; means for supplying said tank with 40 an aeriform fluid under pressure; a wire basket supported in the upper part of the tank with an interval of space between it and said mass of saturated sponges; and a mass of dry sponges contained in said basket, substantially as specified.

45 9. In a carbureter, the combination of a closed tank having a dome with a vertical aperture; a curved disk having a central screw-threaded aperture and fitting the central part 50 of the dome on the inner surface thereof; a tube having exterior screw-threads and engaged thereby with the central aperture of said disk; a basket of wire-netting fastened to the disk on the edge thereof; a mass of sponge 55 contained in said basket; and a nut fitting upon the outer end of said tube and being in contact with the exterior surface of said dome at the center thereof, substantially as specified.

60 10. In a carbureter, the combination of a closed tank having a dome with a central aperture; a curved disk having a central screw-threaded aperture and fitting the central part 65 of the dome on the inner surface thereof; a tube having exterior screw-threads and engaged thereby with the central aperture of

said disk; a basket of wire-netting fastened to the disk on the edge thereof; a mass of sponge contained in said basket; a nut fitting on the outer end of said tube and adapted to hold said disk in snug contact with the inner 70 side of the dome; and a chamber on the exterior of said dome into which said tube opens, substantially as specified.

11. In a carbureter, the combination of a closed tank having a dome with a central aperture; a curved disk having a central screw-threaded aperture and fitting the central part 75 of the dome on the inner surface thereof; a tube having exterior screw-threads and engaged thereby with the central aperture of the 80 disk; a basket of wire-netting fastened to the disk on the edge thereof; a mass of sponge contained in said basket; a nut fitting on the outer end of said tube and adapted to hold 85 said disk in snug contact with the inner surface of the dome; a chamber on the exterior of said dome into which said tube opens; a pressure-gage; and a pipe connecting said chamber and pressure-gage, substantially as specified.

90 12. In a carbureter, the combination of a closed tank having a dome with a central aperture; a curved disk having a central screw-threaded aperture and fitting the central part 95 of the dome on the inner surface thereof; a tube having exterior screw-threads and engaged thereby with the central aperture of the 100 said disk; a basket of wire-netting fastened to the disk on the edge thereof; a mass of sponge contained in said basket; a nut fitting on the 105 outer end of said tube and adapted to hold said disk in snug contact with the dome; a chamber on the exterior of said dome into which said tube opens; and an outlet-pipe passing out of said chamber, substantially as specified.

13. In a carbureter, the combination of a closed tank divided by a horizontal screen or perforated partition into two compartments; a supply-pipe adapted to discharge into the 110 lower compartment a liquid hydrocarbon and an aeriform fluid under pressure; a mass of sponge upon said screen or partition; a mass of wicks connected to the mass of sponge and having their loose ends protruding through 115 said screen or partition and extending down into said lower compartment; a dome for said carbureter having a central aperture; a wire basket having a cover provided with a central aperture; a screw-threaded tube fitting the 120 aperture of the said cover and the said aperture of the dome; a mass of sponge in said basket; a nut on the said tube; a chamber on the exterior of said dome into which said tube opens, a pipe communicating with the chamber 125 of said dome; and a valve in the last-named pipe, substantially as specified.

14. In a carbureter, the combination of a closed tank; a closed tank divided by a horizontal screen or perforated partition into two 130

compartments; a supply-pipe adapted to discharge into the lower compartment a liquid hydrocarbon and an aeriform fluid under pressure; a mass of sponge upon said screen or partition; a mass of wicks connected to the mass of sponge and having their loose ends protruding through said screen or partition and extending down into said lower compartment; a dome for said carbureter having a central aperture; a wire basket having a cover provided with a central aperture; a screw-threaded tube fitting the aperture of the said cover and the said aperture of the dome; a mass of sponge in said basket; a nut on said

tube; a chamber on the exterior of said dome into which said tube opens; and an outlet-pipe passing out of said chamber, a pipe communicating with the chamber of said dome; and a filtering-chamber in said pipe, and a valve in said pipe intermediate its filtering-chamber and the dome of the carbureter, substantially as specified.

In testimony whereof I affix my signature in the presence of two witnesses.

ANDERS AKESON.
